UNITED STATES PATENT OFFICE.

WILLIAM H. CONWAY, OF HARRISON, MARYLAND.

IMPROVED GAFF FOR VESSELS' SAILS.

Specification forming part of Letters Patent No. 33,295, dated September 17, 1861.

To all whom it may concern:

Be it known that I, WILLIAM H. CONWAY, of Harrison, in the county of Dorchester and State of Maryland, have invented an Improvement in Gaffs for Sail and other Vessels, of which the following is a full, clear, and exact description, reference being had to the accompanying drawings, making part of this specification, of which—

Figure 1 is a top view; Fig. 2, a side elevation, and Fig. 3 an end view.

The object of my invention is to avoid the chafing of the mast in setting and striking sail, and at the same time to relieve the canvas and rope of all strain in the dropping of the peak. To these ends the jaws are constructed out of any timber which presents a naturally-formed fork or crotch, and they are adjusted to the mast, when they remain permanently fixed in the setting and striking of the sail. The jaws have an extension like the handle of a pitchfork, to which is attached by means of a strong hinge the peak or outer end of the gaff. This arrangement will be more distinctly understood by reference to the drawings, in which—

A represent the jaws that encircle the mast; B, the extension of the jaws, to which is attached by means of the hinge *a* the peak or outer end C of the gaff. The jaws with their extension are adjusted to the mast by means of the throat-halyard, which passes through the hook *b*, and the mast-rope, which is attached to the hook *c*. In the setting and striking of the sail these jaws remain stationary and there is no abrasion of the mast, as there is in cases when the gaff is made of one piece, the sail being trimmed wholly by means of the hinged peak acted upon by the peak-halyard. Moreover, by my improvement the sail is not strained in dropping the peak, which is the case with gaffs as heretofore constructed, for other gaffs being made whole without joint, and the throat-halyard hook forming the center of motion, the jaw end of the gaff acts upon the throat of the sail in the shape of a lever and draws up the sail vertically and diagonally, often lifting the boom bodily. It is obvious that from my improvement no such result can flow. It renders the construction of the gaff cheap, for the jaws

may be of natural growth, and when one part is worn out or injured it can be renewed without the renewal of the whole, and these considerations conduce to show its durability. It tends to make the gaff much easier to the sail in dropping the peak, as there is no strain on the ropes or canvas. By it the peak when down is much easier set up, as the jaws are not grinding the mast, and the jaws when up are always in the proper place, and the dropping of the throat of the sail is not required when jibing.

I have stated above that my jaws may be formed out of timber which presents a naturally-formed fork or crotch. The method heretofore generally adopted of making the jaws or yoke was to bolt onto the inner end of the gaff separate pieces fashioned into the desired shape. This plan is laborious, expensive, and insecure when compared with mine, which involves simply the dressing of the crotch, and secures great strength and durability. Sometimes, however, gaffs may have been made out of sticks which prevented natural forks to form the cheeks or jaws, although I am not aware that such is the fact; but these could only be used on small vessels, because timber long and straight enough for vessels of the larger class with a crotch of natural growth cannot readily be found, and if it could it would be too heavy for either gaffs or booms. Hence the practice in large vessels has always been to select for these and like purposes the lightest timber, as pine, for instance; but as this usually grows without branching it resulted as a necessity that cheeks should be bolted on to form the jaws. By hinging the peak of the gaff to the jaws, as above described, I am enabled to secure the advantages of the natural crotch in the largest vessels, for the jaws may be of such timber as branches in its growth, such as oak, while the peak may be, as usual, made of pine or like wood, and thus avoid the too great weight of the gaff.

Having thus described my improvement in gaffs, what I claim therein, and desire to secure by Letters Patent of the United States, is—

1. Dividing the gaff into two parts called the "jaws" and the "peak," and uniting or con-

necting them together by means of a hinge, whereby the chafing or abrasion of the mast is prevented and the strain upon the canvas relieved in the striking of the sail, substantially as described.

2. In combination with a gaff so divided and hinged, making the jaws thereof out of tim-

ber which presents a naturally-formed fork or crotch, as and for the purposes described.

W. H. CONWAY.
